UNITED STATES PATENT OFFICE.

GEORGE N. BUCK, OF MATTOON, ILLINOIS.

TAG-FASTENER.

SPECIFICATION forming part of Letters Patent No. 286,112, dated October 2, 1883.

Application filed August 17, 1883. (No model.)

To all whom it may concern:

Be it known that I, GEORGE N. BUCK, of Mattoon, in the county of Coles and State of Illinois, have invented a new and useful Improvement in Tag-Fasteners, of which the following is a full, clear, and exact description, reference being had to the annexed drawings, forming part of this specification.

This invention relates to fasteners for securing tags to rolls of cloth; and the invention consists of the novel construction hereinafter described and claimed.

In the drawings, Figure 1 is a perspective view of a tag and fastener showing my invention. Fig. 2 is a perspective view of a roll of cloth, showing the tag attached thereto; and Fig. 3 is a side elevation of the roll of cloth, partly broken away and in section, showing the tag attached thereto, and also showing, in dotted lines, the manner of inserting the fastener into the roll.

The fastener A consists of a single piece of wire or other suitable material, which is doubled upon itself like a staple and inserted 25 through the tag B, and then has its extreme ends a, which are pointed, bent up in the same direction with each other, and in a direction at right angles with the plane of its body or prongs, to form catches for holding the fastener 30 in place. The prongs b, which incline outwardly at the ends, are thus adapted to be inserted between the folds of cloth in the roll C until the back of the tag is in contact with the end of roll, and as the ends a are inclined toward the 35 tag, any outward movement of the fastener will cause the said ends to sink into the adjacent fold or folds of the cloth and prevent its accidental withdrawal. The board D, upon which the roll of cloth is commonly wound, serves as 40 a guide for the prongs b in the insertion of the same under the central fold, e; but where the roll is made up without such central board the folds, if very compactly rolled, may be separated by the insertion of a pencil between them 45 to form an opening for the prongs, which latter are adapted to be sprung together to fit said opening.

In order that the tag B may be braced in a given position by the fastener, and at the same 50 time be capable of being thrown into a plane

parallel with the fastener, as shown in dotted lines in Fig. 3, the loop d, which bears against the face of the tag, is bent up out of the plane of the prongs b approximately in the direction of the ends a. With such a construction the 55 tag can be turned out of the way of the fingers to enable the fastener to be firmly grasped, so as not to tear or break the tag in attaching it to the goods, and when the fastener is nearly 60 in position the tag may be allowed to drop into position at right angles to the fastener and be pressed up against the end of the roll. The tag will thus be held rigidly in position by the contact of the roll with its back and that of the loop d with its face. 65

To hold the tag at the loop end of the fastener, the prongs b, after being inserted through the tag, are bent inward toward each other, as shown in Fig. 1 at e, and the ends of the prongs are sprung apart to give them a better hold 70 upon the cloth and prevent turning, as well as for the purpose above described.

I am aware that a wall-paper tag-fastener has been provided with flaring prongs made of springy metal, adapted to be compressed together and inserted into the center of a roll of paper. I am also aware that such flaring prongs have been provided at their ends with hooks or bent points extended in opposite directions in the plane of the fastener or prongs. 75 Such a construction, while perfectly adapted to a roll of cloth having a circular opening at the center, cannot well be used in a wide opening or next to a flat board at the center of the roll, because the strain exerted upon the fastener 80 by the roll will cause it to turn into coincidence with the plane of the opening, and thus throw the hooks out of engagement with the cloth. In my invention the hooks are bent at right angles to the plane of the prongs, so that the 85 plane of the prongs will lie in the plane of the opening when the points are in the cloth, and the contact of both prongs with the same fold of cloth or with the board will prevent the fastener from turning and disengaging the 90 points. 95

What I claim is—

The combination, with a tag, of a tag-fastener having two prongs, both of which are passed through the tag, and are provided with 100

pointed ends bent upward in a direction at an angle with the plane of the prongs, and a central loop which is bent upward out of the plane of the prongs, substantially as shown and described, whereby the tag may be turned to a position parallel with the plane of the prongs, to facilitate the insertion of the prongs into a roll of cloth, and be braced by the loop when

pressed against the end of the roll in a position at right angles with the prongs, as set forth.

GEO. N. BUCK.
